(57) **CLAIM**

We claim the ornamental design for a display panel of a programmed computer system with a graphical user interface, as shown and described.

DESCRIPTION

The FIGURE is a front view of a display panel of a programmed computer system with a graphical user interface.

The broken lines of the display panel are included for the purpose of illustrating environmental structure; the broken lines form no part of the claimed design.

Wagner James Au May, wanna buy a San Francisco condo in the heart of North Beach with this view for \$260K? Slight drawback: It's a 10x10 studio with the kitchen in the living room (which is also the bedroom.) but LOOK AT THE F---ING VIEW.
